UNITED STATES PATENT OFFICE.

GEORGE T. CHAPMAN, OF WHITE PLAINS, ASSIGNOR OF ONE-HALF TO
WILLIAM HARVEY MERRITT, OF NEW YORK, N. Y.

HOOF-EXPANDER.

SPECIFICATION forming part of Letters Patent No. 431,022, dated June 24, 1890.

Application filed May 1, 1889. Serial No. 309,148. (No model.)

To all whom it may concern:

Be it known that I, GEORGE T. CHAPMAN, a citizen of the United States, residing at White Plains, in the county of Westchester 5 and State of New York, have invented certain new and useful Improvements in Hoof-Expanders; and I do hereby declare the following to be a full, clear, and exact description of the invention, such as will enable others 10 skilled in the art to which it appertains to make and use the same.

My invention consists of an adjustable extension-plate of two parts adapted to range along the sole of the foot from the heel nearly 15 to the toe and having a pair of jointed struts on each part—one pair for the heel and the other pair for the forward part of the hoof—all comprising an expander for use in correcting the deformities of feet that are arched 20 unduly in the sole from heel to toe and also contracted at the heel. In some cases the toe-struts are dispensed with, all as herein-after fully described, reference being made to the accompanying drawings, in which—

25 Figure 1 is a plan view of the bottom of a foot and the expander applied to it, with a part of the heel portion of the expander broken off. Fig. 2 is a longitudinal section of the same from heel to toe, and of a bar- 30 shoe, such as it is preferred to use to keep the expander in place. The figure shows the arched sole. Fig. 3 is a rear end view of the expander, foot, and shoe. Fig. 4 is a plan view, same as Fig. 1, showing the heel-struts 35 in the later period of the use of the expander, when they are mainly taking effect for expansion of the heel. The extension-plate consists of the two short metal parts *a* and *b*, of approved length, breadth, and thickness, to 40 apply to the bottom of the foot, as shown, a condition for adjusting lengthwise, one being placed on the other and connected by the studs *c* of one projecting through the slot *d* of the other, with the adjusting-screw *e* fitted 45 to part *a* and bearing against the end of part *b*, suitably for effecting the extension, the studs having heads to keep the two parts in contact, and the part *a* having the laterally-projecting arms *f* at the rear end.

50 The part *a* of the expander is placed beneath

part *b*, and has near the rear end and on the upper side the heel-struts *g*, pivoted on it near the longitudinal center of the plate, and so that they project laterally over and are supported by the arms *f* of the plate the 55 whole length of their lateral range, or nearly so. The struts turn upward abruptly near the outer ends and terminate in short spurs *i*, one of which on each strut is engaged in the side of the hoof in the clefts of the heel a little 60 in advance of the rear angles of the hoof thereat when the attachment is first applied, as in Fig. 1, the struts having considerable inclination forward relatively to the hoof from their points of contact thereon in said 65 figure. The part *b* of the extension-plate has toe-struts *h* similarly pivoted to it a little back of its forward end, but on the under side, which struts project therefrom laterally and forwardly, and are suitably perforated 70 near the outer ends to be nailed at *i'* to the hoof, said ends being set in recesses of the hoof flush with the bottom, so that they make no interference with the shoe *j*. The front end of the plate is at the same time fitted to 75 bear against the shoulder *k*, made in the sole of the foot, so as to have a direct forward thrust on the toe of the sole, while struts *h* effect lateral expansion of the fore part of the hoof a short distance back of the toe; but 80 these struts are principally used in case of deficient sole-bearing for the end of the plate and as an auxiliary means of holding the plate in place, and struts *g* effect longitudinal ex- 85 tension of the sole and lateral expansion of the heel, the adjusting-screw *e* being shifted from time to time as the foot yields to the treatment. As the sole elongates, the prongs *i* of the heel-struts not at first engaged with the heel swing backward and around the 90 angles *m* of the heel, so that the notches between the prongs embrace the angles of the heel, as shown in Fig. 4, about when the proper elongation of the sole has been pro- 95 duced, for better contact to deliver the more lateral thrust, taking more laterally expansive effect as the struts gradually assume that direction through the extension of the duplex extension-plates.

At the front end the expander is held in 100

position by the "bite" of the end on the shoulder *k* of the sole, and by the struts *h*, attached to the hoof above the shoe, and at the rear said expander is mainly held in position by the bar *n* of the shoe, on which the plate *a* rests; but it is also held to some extent by the prongs of the struts *g*.

The manner of connecting the two parts of the extension-plate and of effecting the *ext*ension may be varied at will, and I do not limit myself in these respects to the particular arrangement shown.

It will be seen that a foot arched in the sole so that it is shorter than the normal condition, and also contracted at the heel, which is usually the case with such arched feet, may with this improved expander be effectually treated and restored to the proper form without much trouble or care after the attachment of it to begin with, it being only necessary to occasionally shift the adjusting-screw.

When the sole is in good condition and affords substantial connection of part *b* of the expander by the shoulder *k*, the struts *h* may be dispensed with. They are mainly used to keep the front end in position. When the nature of the sole is such that the shoulder *k* is not reliable, which is sometimes the case, owing to a decayed and brittle condition to which the soles are subject, these struts then serve, together with what resistance the shoulder *k* does afford, to produce the back-thrust on the heel-struts, which is most important.

What I claim, and desire to secure by Letters Patent, is—

1. The improved hoof-expander consisting of the toe and heel extension-plate and the extending screw, said plate having heel-struts jointed to the heel part, the toe end adapted to engage with the bottom of the sole back of

the toe, while the heel-struts engage with the sides of the hoof in the heel-clefts, substantially as described.

2. The improved hoof-expander consisting of the extension-plate having the front end *adapted* to engage the shoulder *k* in the sole of the foot, the toe-expanding struts adapted to engage with the bottom of the hoof back of the toe, and the heel extending and expanding struts adapted to engage the sides of the *50* hoof in the heel-clefts, substantially as described.

3. The improved hoof-expander consisting of the extension-plate having the laterally-projecting strut-supporting arms of the heel *part*, the heel extending and expanding struts pivoted on the upper side, supported on said arms, and having the upwardly-projected and pronged terminals adapted to engage the sides of the hoof in the heel-clefts, said extension-plate also having the toe-struts on the toe part of the same, substantially as described.

4. The improved hoof-expander consisting of the duplex extension-plate having the toe and heel struts on the respective parts, said *65* heel-struts having the upwardly-projected and pronged terminals adapted to first engage the sides of the hoof in the heel-clefts near the angles of the same by one of the prongs, and subsequently engage said angles in the notch *70* between the prongs through the change of the struts by the progressive adjustment of the expander, substantially as described.

In testimony whereof I affix my signature in presence of two witnesses.

GEO. T. CHAPMAN.
